UNITED STATES PATENT OFFICE.

WILLIAM GRAY, OF HARTFORD, CONNECTICUT, ASSIGNOR TO THE GRAY TELEPHONE PAY STATION COMPANY, OF SAME PLACE.

TELEPHONE TOLL APPARATUS.

SPECIFICATION forming part of Letters Patent No. 593,962, dated November 16, 1897.

Application filed February 8, 1897. Serial No. 622,578. (No model.)

To all whom it may concern:

Be it known that I, WILLIAM GRAY, a citizen of the United States, and a resident of Hartford, in the county of Hartford and State 5 of Connecticut, have invented certain new and useful Improvements in Telephone Toll Apparatus, of which the following is a full, clear, and exact description, whereby any one skilled in the art can make and use the same.

10 The object of my invention is to provide an improved device by the use of which a signal sounded by the payment of toll for the use of the telephone instrument at any station may be clearly heard at the central office, the 15 sound being conducted over the line-wire in the same way as a vocal sound.

A further object is to dispense with the use of any hollow or tubular deflector for this purpose and to make use of the post or part used 20 to support the transmitter.

To this end my invention consists in the combination of the coin channel-plate, the transmitter-arm and transmitter, and a rigid connecting-tie; and it further consists in the 25 details of the parts making up the apparatus and in the combination of such parts, as more particularly hereinafter described in the claims.

Referring to the drawings, Figure 1 is a detail view, in side elevation, of a part of a telephone toll apparatus embodying my improvement. Fig. 2 is a detail plan view showing the top of the signal-box and relative location 30 of the transmitter-support and channel-plate.

35 In the accompanying drawings the letter *a* denotes a back board or like support for a set of telephone instruments such as are in common use, including the magneto-bell, a telephone, transmitter, and battery. In addition to these parts in my improved system of mechanical signals in a toll-collecting device a signal-box *b* is used, such box containing a coin channel-plate *c* and signals *d*, usually bells or gongs, with a part arranged so 40 that the falling coins inserted through a slot in the top of the signal-box shall in falling strike the signal, the sound of which is conveyed to the central office. In this system for several years a hollow post or collapsible 45 tube, called a "deflector," has been used, such tube being arranged over an opening in the wall of the box and with its upper end extend-

ing to a position substantially opposite the mouth of the transmitter, so that the sound of the signal within the signal-box may be 55 more readily conducted without obstruction to the diaphragm of the transmitter.

I have found by experiment that the tubular deflector may be dispensed with without disadvantage, provided close contact can be maintained between the metal channel-plate to which the signal-bell is attached and the metal post or part on which the transmitter is supported. In the form of my improvement herein illustrated a hole *a'* is made in the 60 cover of the signal-box, and over this is secured the base *e'* of a transmitter-post *e*. To this post the arm *f'* of the transmitter *f* is pivoted, so as to permit of the usual up-and-down adjustment of the transmitter to accommodate the various heights of the users 65 of the instrument. A rigid tie *g* is firmly connected to the channel-plate and extends from there to the base of the transmitter-post, to which it is also secured, forming, as near as 70 possible, a metallic circuit from the signal-bell *d* to the transmitter *f* for conducting the sound of the bell to the transmitter. The best results are obtained when the contact 75 and connection between the transmitter-support and the metallic channel-plate are close 80 and practically continuous.

In prior apparatuses of this general class as used for a number of years by me the slot-plate and channel-plate have been secured to 85 the wooden top of the signal-box, and at a distance therefrom a metallic transmitter-support has been secured. In instances where such transmitter-support has been solid the signals sounded by the coin have been very 90 faint and practically indistinguishable over any considerable length of wire. By the use of a hollow deflector a great gain in clearness of the signal was obtained. The fact that the coin channel-plate and the transmitter-support 95 were both fastened to the same side or wall of the signal-box would aid the transmission of the sound made by the falling coin, but by directly connecting the channel-plate and transmitter-support, either by placing 100 these two parts in actual contact or by the use of a rigid tie, as *g*, a gain is made in clearness and distinctness of the signal. In fact, I have proved by experiment that this direct

contact of the two parts, or their connection by a rigid tie, is essential to the clear sounding and transmission of the signals in the apparatus.

5 The metallic part of the channel-plate and the transmitter-support, when such parts are in actual contact or connected by metal strips, are more or less charged with a current of electricity, but whether this fact is or not a 10 factor in the better transmission of the signals has not yet been clearly determined, but the fact that a greatly-improved signal device can be obtained by the means described has been clearly shown by tests.

15 I claim as my invention—

1. In combination with the receiving and transmitting part of a telephone apparatus, a metallic channel-plate supporting a signal

device, a metallic post supporting a transmitter and a metallic connection uniting the 20 transmitter-post and the channel-plate.

2. In combination with the receiving and transmitting part of a telephone apparatus, a metallic channel-plate supporting a signal device, a signal-box containing the channel- 25 plate the wall of the signal-box with an opening therethrough, a metallic post supporting a transmitter and covering the opening through the wall of the signal-box, and a metallic connection uniting the transmitter-post 30 and the channel-plate.

WILLIAM GRAY.
